UNITED STATES PATENT OFFICE.

ROBERT L. ELLERY, OF TOLEDO, OHIO.

PRESSING GLASS.

Application filed January 20, 1926. Serial No. 82,392.

This invention relates to the pressing of glassware, and particularly to the pressing of glass plates.

The invention has for its object to provide a method of and apparatus for pressing glass between two approaching surfaces in such a manner as to spread the glass evenly and form clear sheets which will require the minimum of grinding and polishing. Other 10 objects of the invention will appear as the description proceeds.

In the accompanying drawing, forming a part of this specification, Figure 1 is a somewhat diagrammatic side view of one form 15 of apparatus embodying my invention; Fig. 2 is a detail showing somewhat diagrammatically my method of ejecting the finished article from the mold; Fig. 3 is a somewhat diagrammatic showing of the means for 20 moving the mold carrier; Fig. 4 is a detail showing a portion of the mold operating means; Fig. 5 is a somewhat diagrammatic showing of an alternative form of mold carrying and operating means.

25 In the structure shown in Fig. 1 there is a mold-carrier 10 mounted upon a horizontal axis 11. In the structure shown there are four molds mounted upon the mold-carrier. The mold shown at the right of Fig. 1 will 30 be described first. In this structure there is a stationary plate 12 preferably mounted at a slight angle to the vertical. Opposite this plate there is a movable plate 13. The movable mold-plate is pivoted at 14 for 35 oscillation towards and from mold-plate 12.

An arm 15 extends from a rock shaft 16 mounted in the mold-carrier and is connected by an adjustable link 17 to the movable mold-plate 13. Another arm 18 extends 40 downward from rock shaft 16 and terminates in an anti-friction roller 19. A lever 20 is pivoted at 21 to a stationary portion of the frame 22 supporting axis 11. One arm 23 of the lever 20 extends downward 45 and is connected at 24 to the piston rod 25 of a piston 26 working in a cylinder 27. The other arm 28 of lever 20 extends upward and bears a plate 29 adapted to contact roller 19 and oscillate rock shaft 16. Rock shaft 50 16 is provided with a third arm 32 bearing a roller 33 and actuated in a manner which will be described later.

The upper end of the oscillating mold-plate is provided with a flange 30 adapted to 55 pass over the outer end of mold-plate 12. The stationary frame 22 is provided with

plates 31 at opposite ends of the mold-plates 12 and 13 when the mold is in the position at the right, as shown in Fig. 1.

With the parts in the position shown in Fig. 1 the starting valve is actuated, the valve 34 controlling cylinder 27 being moved in a well-understood manner to a position admitting air under pressure through pipe 35 to the right end of cylinder 27. When piston 26 moves to the left from the position shown in Fig. 1, lever 20 is actuated to move arm 18, rock shaft 16, arm 15, link 17 and oscillating mold plate 13.

It will be understood that before the starting valve is operated a suitable charge of glass has been dropped between the mold plates, and as plate 13 is swung to the right this charge of glass is gradually spread upward between the mold plates. As will be readily seen, the glass first approaches final thickness at the lower side of the sheet and the glass is spread upward from the comparatively thick upper portion of the wedging charge of glass to form the upper portion of the sheet, the portion of glass which is being moved upward remaining thicker than the lower portion until the sheet is finally completed. In this way the glass is spread to sheet form with a minimum movement of a glass through a narrow space between opposed plates. The glass is spread much in the same way it would be by rolling it upon a table, and at the same time the opposed surfaces are both held perfectly flat and level by the opposed mold plates so that there is no possibility of the formation of bends or waves such as are readily formed when the glass is rolled.

After the glass plate has been pressed in the mold shown at the right in Fig. 1, the mold-carrier is actuated by introducing air in a manner which will be readily understood into mold turning cylinder 36, shown in Fig. 3. This cylinder is mounted upon a horizontal axis 37 and has attached to its piston rod a rack 38 adapted to mesh with a gear 39 attached to the mold-carrier. The rack is raised and lowered into and out of mesh with gear 39 by means of a cylinder 40. There is diagrammatically indicated a valve 41 controlled by the raising and lowering of the rack for controlling the movement of air to opposite ends of cylinder 36 in a manner that will be readily understood and which forms no part of this invention.

In the construction shown there are four molds upon the carrier, and, therefore, the carrier is rotated through 90° at each movement of rack 38 so that the mold originally in the position shown at the right of Fig. 1 will be moved to the lower position shown in dotted lines at 12^a on Fig. 1. At the third movement the mold is raised to the position shown at 12^c at the top of Fig. 1. As the mold approaches this last described position, roller 33 contacts a cam 42 fixed upon the stationary frame in position to open the mold, as shown at 12^c.

While the mold is open at 12^c the formed plate-glass 43 is slid from the mold by an ejector plunger 44 actuated by a cylinder 45. Any desired means may be provided for receiving the molded plate of glass. The next movement of the mold carrier returns the mold to its original position ready to receive another charge of glass. It will be readily understood that at each movement of the mold-carrier a charge is placed in the mold occupying the position shown at the right of Fig. 1 while a plate is being ejected from the mold shown at the top of Fig. 1 and plates are cooling and setting in the other two positions.

It will be readily understood that fewer or more molds may be used as desired to give the glass the proper setting time.

The modified form shown in Fig. 5 operates upon substantially the same principle. In this structure shown fragmentarily and somewhat diagrammatically in Fig. 5, there is a rotating table 50 carrying a series of molds 51, but one of which is shown. Each mold comprises a stationary mold-half 52 and an oscillatable mold-half 53. In the construction shown, the mold-half 53 is provided with end plates 54. A rock shaft 55 mounted adjacent the hub of table 50 is provided with an arm 56 carrying a roller 57 and connected and by means of an adjustable link 58 to the oscillatable mold-plate 53. A cylinder 59 is mounted above the position of roller 57 connected to the mold in glass receiving position, and the piston rod 60 of cylinder 59 carries a contact plate 61 adapted to press upon roller 57 and bring arm 56 and link 58 into line and close mold-plate 53 against mold-plate 52.

In the construction shown, arm 56 is provided with a lug 57' carrying a cam roller 58 adapted to run upon a cam 59 which opens the mold at proper times and allows it to be closed when in glass-receiving position. It will be readily understood that the table 50 is moved intermittently and the molds are charged successively as they reach charging position and are closed successively by the operation of cylinder 59. It is thought that the operation of this apparatus will be apparent without further description thereof.

Metal molds for glass or other refractory

materials that are either molded or pressed when made plastic or liquid by heat, are usually made of cast iron or steel. Owing, however, to the porous nature of cast iron, there is a rapid oxidization and disintegration of iron when exposed directly to the action of heat, and molds made of iron are, therefore, not entirely satisfactory, especially when used in press operations as the surface in contact with the hot materials quickly becomes rough and the glass or other material clings to these rough surfaces, making a product of poor quality.

It is found that if molds of this character are protected by a dense, close grain material, such as nickel, the life of the mold is enhanced and the quality of the product is greatly improved. Nickel is close grained and capable of taking a high mirror polish which it will impart to the molded or pressed article when the article is held in the mold until it is cool enough to retain its shape. It is much more resistant than cast iron or steel to the action of heat, having the melting point averaging approximately 500° F. higher than iron. It does not oxidize, except in the presence of iodine, chlorium, bromine, fluorium, cyanogen and these elements are not present in harmful quantities in ordinary glass or die casting operations.

Nickel is deposited on the mold surfaces preferably by electrolysis and whenever possible directly on to the molds without the medium of a copper plating for the reason that coefficient of expansion between the iron and nickel is nearer than iron and copper or nickel and copper. Therefore, where the nickel is deposited directly on to the iron surface to be protected, there is less likelihood of flaking, owing to unequal expansion of the two metals. In the case of nickel and iron this is about as 5 is to $6\frac{1}{2}$. The nickel having the lower rate of expansion and being in direct contact with the molten material will, owing to its lower rate of conductivity (about as 5 is to 9), be much hotter than the iron backing, which tends to equalize the ratio of expansion between the two metals and the malleable nature of nickel easily adapts it to this slight variation. Nickel plating will withstand temperatures up to red heat without flaking or loosening from the mold. A mold, therefore, plated with nickel will withstand the corroding action of the material being molded, will take and retain a higher polish, giving a smoother and more finished article than is the case with the present practice, and will add greatly to the life of the mold.

I wish it understood that my invention is not limited to any specific construction, arrangement or form of the parts as it is capable of numerous modifications and changes without departing from the spirit of the claims.

Having thus described my invention, what I claim as new and desire to secure by Letters Patent is:

1. In a glass press, a mold carrier mounted upon a horizontal axis, a series of molds mounted on said carrier, each mold comprising a fixed mold plate and an oscillatable mold plate pivoted near one edge upon a horizontal axis, said mold plates being arranged to form a V-shaped opening therebetween when the oscillatable mold plate is moved to open position, and to press a plate therebetween when the oscillatable plate is moved to closed position, means to move said carrier intermittently and means to close the molds successively while the carrier is at rest, said means being in position to actuate the mold having its oscillatable mold plate pivoted at its lower edge. 65
  2. In a glass press, a mold carrier mounted upon a horizontal axis, a series of molds mounted on said carrier, each mold comprising a fixed mold plate and an oscillatable mold plate pivoted near one edge upon a horizontal axis, said mold plates being arranged to form a V-shaped opening therebetween when the oscillatable mold plate is moved to open position, and to press a plate therebetween when the oscillatable plate is moved to closed position, means to move said carrier intermittently and means to close the molds successively while the carrier is at rest, said means being in position to actuate the mold having its oscillatable mold plate pivoted at its lower edge, means to open the molds successively as they reach their upper position and means to eject the pressed glass successively from the open molds. 70
  3. A receiver for molten glass comprising outwardly diverging plate mold members, means for bringing said members into parallelism as a closed mold, an orienting device for bringing said closed mold members into horizontally extending position, releasing means for the plate in the mold, and a discharge device for ejecting the released plate from the mold. 75
  4. In apparatus for pressing sheet glass, a mold comprising two mold plates, means to place said mold plates in receiving position with their pressing faces approximately vertical, but diverging upwardly, means for bringing said mold plates into parallelism as a closed mold, means for placing the mold in a discharging position with the sheet pressed between its mold faces substantially horizontal, means for opening the mold, and means for ejecting the pressed plate from the mold horizontally. 105
  5. In apparatus for pressing sheet glass, a mold plate arranged with its pressing sur-
- face substantially vertical when in glass receiving position, a co-operating mold plate pivoted near the lower edge of the first said mold plate, means to swing said co-operating mold plate about said pivot to close the mold and press a sheet of glass between the mold surfaces, means to move the mold from its receiving position to a substantially horizontal discharging position, and means to discharge a pressed sheet from the mold horizontally while the mold is in substantially horizontal position. 110
6. In apparatus for pressing sheet glass, a series of molds each comprising oppositely disposed mold plates, means for positioning each mold in succession in receiving position with its molding space substantially vertical, means adjacent said receiving position for operating upon each mold in succession and pressing the mold plates together while they are in receiving position, means to move the molds in succession to a discharging position, and means at the discharging position to eject sheets of glass 80 from the molds successively. 85
7. In apparatus for pressing sheet glass, a series of molds each comprising two mold plates hinged together adjacent one edge, means for placing each mold in succession in receiving position with its hinged side downward and with the plates diverging upwardly, means adjacent the receiving position for bringing said plates into parallelism as a closed mold, means for moving the molds in succession into a discharging position with the pressed sheet therein substantially horizontal, and ejecting means adjacent the discharging position adapted to eject pressed sheets horizontally from the molds in succession. 90
8. In apparatus for pressing glass, a series of molds each comprising two mold plates, means for placing each mold in succession with its molding space substantially vertical, a cylinder and piston, means operable by said piston for pressing the mold plates together while in receiving position, means to move the mold in succession from receiving position to a discharging position with its mold cavity substantially horizontal, cam means for separating the plates of each mold as the mold approaches discharging position, another cylinder and piston, and means operable by the last said piston for ejecting 115 a molded article horizontally from each mold in succession at the discharging position. 110

In testimony whereof I have hereunto signed my name to this specification.

ROBERT L. ELLERY.
